UNITED STATES PATENT OFFICE

2,422,413

MARBLE MAKING MACHINE

Oris G. Hanlon, Massillon, Ohio

Application May 23, 1944, Serial No. 536,971

3 Claims. (Cl. 49—14)

1

The present invention relates to new and useful improvements in the art of making glass articles, and more particularly to an apparatus for making toy glass marbles, and has for its primary object to improve the construction of machines whereby to increase the production thereof.

A further important object of the invention is to provide a novel shearing mechanism for cutting the globules of molten glass to form the marbles and embodying a shearing device capable of increasing the number of marbles cut from the molten mass and also providing tilttable chutes receiving the marbles from the discharge funnels, the chutes being actuated for conveying the marbles alternately to separate rolling machines whereby to prevent contact of the marbles with each other during the rolling action.

A still further object of the invention is to provide an apparatus of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view with parts broken away and shown in section.

Figure 2 is a vertical sectional view taken approximately on the line 2—2 of Figure 5 illustrating the shearing mechanism with one of the end knives in cutting position.

Figure 3 is a similar view showing the center knife in cutting position.

Figure 4 is a similar view showing the other end knife in cutting position.

Figure 5 is a horizontal sectional view taken substantially on a line 5—5 of Figure 1.

Figure 6 is a fragmentary vertical sectional view taken substantially on a line 6—6 of Figure 1.

Referring now to the drawings in detail, wherein for the purpose of illustration I have disclosed a preferred embodiment of the invention, the numeral 5 designates a suitable glass furnace within which glass of one or more colors is adapted to be melted, the resultant stream 6 gravitating downwardly through an opening (not shown) in the bottom of the furnace.

Positioned below the furnace 5 is a cutter guide designated generally at 7 having an opening 8 extending horizontally therethrough of substan-

tially rectangular shape in cross section to define a top section 9 and a bottom section 10, the top section 9 having a cup 11 formed therein positioned in the path of flow of the molten glass 6 and into which the glass is deposited from the furnace.

The bottom section 10 is formed with a pair of spaced funnels 12 and 13 offset from the cup 11 at opposite sides thereof.

10 A cutter bar 14 is slidably mounted in the opening 8 and is reciprocably actuated by a rod 15 attached thereto and operatively connected to a suitable operating mechanism (not shown).

The cutter 14 is formed with a front cup 16, a 15 rear cup 17 and an intermediate cup 18. Recessed in the upper surface of the cutter bar 14 immediately above each of the cups therein is a circular beveled knife 19 adapted to shear a globule 20 from the bottom of the molten mass 6 20 as the same gravitates through the cup 11 into one of the cups of the cutter bar.

A plate 21 is supported beneath the guide 7, the plate having discharge openings 22 and 23 therein, a pair of such openings being provided adjacent the funnels 12 and 13.

25 Chutes 24 and 25 are positioned immediately beneath the funnels 12 and 13, respectively, each of the chutes being rockably supported on a pin 26 carried by the plate 21 at a point between the openings 22 and 23, the ends of the chutes being positioned immediately above said openings.

The chute 24 is operated by an actuating mechanism which comprises an upstanding arm 27, secured to one end of the pin 26 and to which a link 28 is pivotally attached at one end and to the other end of which is pivotally attached the lower end of a trip lever 29 which extends vertically and is pivotally attached, as at 30, to the side of the guide 7. The chute 25 is likewise operated by a similar actuating mechanism comprising an upstanding arm 27' secured to one end of the pin 26' and to which a link 28' is pivotally attached at one end and to the other end of which is pivotally attached the lower end of 40 a trip lever 29' which extends vertically and is pivotally attached, as at 30', to the complementary side of the guide 7.

A cam bar 31 is formed on one side of the cutter bar 14 and projects outwardly through the 45 side of the guide 7 through a slot 32, the outer edge of the cam bar 31 having the toothed formations 33 thereon forming the cam hump engageable with the upper end of the lever 29 to actuate the lever to produce a tilting movement of the 50 chutes 24 and 25 during the reciprocating action

of the cutter bar 14. The chute 24 is tilted from the position indicated by the full lines in Figure 6 to the position indicated by the dotted lines in said figure by the toothed formation 33 of the cam bar. The chute 25 is likewise tilted from the position indicated by the full lines in Figure 6 to the position indicated by the dotted lines in said figure by the complementary toothed formation 33 of the cam bar. The chutes 24 and 25 are returned to the full line positions by any suitable means, not shown.

Positioned immediately beneath the discharge openings 22 and 23 in the plate 21 are the marble rolling machines, composed of pairs of helically grooved complementary spaced rollers 34 and 35. Each of the pairs of rollers 35 is provided with oppositely directed grooved ends, only one of such rollers being shown in Figures 1 to 4, inclusive, the respective grooved ends being indicated by the numerals 35^a and 35^b. Each pair of the rollers 34 is similarly provided with oppositely directed grooved ends of like configuration, not shown. The globules of material are deposited onto the rollers by the respective chutes 24 and 25 adjacent the center of the rollers and are caused, through the intermediacy of the oppositely directed grooves, to be fed toward the ends thereof.

In the operation of the device and with the parts shown in the positions shown in Figure 2 of the drawings, the molten glass will be deposited through the cup 11 into the front cup 16 of the cutter bar 14 whereby a forward movement of the cutter bar will sever the globule 20 at the lower end of the molten mass and deposit the same in the bottom of the cup 16, as shown by the dotted lines. When the front cup 16 passes over the funnel 12, as shown in Figure 3, the globule will then be deposited through the funnel onto the chute 24 and from the chute the globule will be deposited onto the inner end of the oppositely directed grooved ends 35^a of the rollers 35 of the rolling machine which functions to continuously twirl and knead the globule and at the same time conveys the same longitudinally so that by the time it reaches the discharge end of the marble rolling machine it is perfectly spherical, hardened and ready for use, subject only to cooling.

When the front cup 16 reaches the funnel 12, the center cup 18 will then be positioned beneath the cup 11 for likewise receiving one of the globules which is cut by a further forward movement of the cutter bar 14 and deposited in the cup 18 from which it is then deposited in the funnel 12, as shown in Figure 4 of the drawings.

During this action, the cam bar 31 functions to trip the chute 24 from the full line position shown in Figure 6 to the dotted line position whereby the globule is then discharged onto the inner ends of the complementary oppositely directed grooved ends of the rollers 34 of the rolling machine.

When the center cup 18 is moved into a position for registering with the funnel 12, the rear cup 17 has then been moved into a position immediately beneath the cup 11 for likewise receiving one of the globules and the cutter bar 14 has then reached the end of its forward stroke and at the beginning of its rear stroke the globule will be cut and deposited in the cup 17 when the cup 17 registers with the funnel 13 whereupon the

globule is deposited therethrough onto the chute 25 for feeding to the inner ends of the oppositely directed grooved ends 35^b of the rollers 35 of the rolling machine.

During the rearward movement of the cutter bar 14, the center cup 18 likewise receives one of the globules and deposits the same into the funnel 13 for subsequent deposit onto the inner ends of the rollers 34, the center cup 18 thus feeding the globule to both the funnels 12 and 13 while the front cup 16 feeds the globules only to the funnel 12 and the rear cup 17 feeds the globules only to the funnel 13.

By reason of this construction, production of the machine is materially increased and the tiltable chutes 24 and 25 distribute the globules to the respective sets of rollers of the rolling machine so as not to permit contact of the marbles with each other during the rolling action.

It is believed the details of construction and manner of operation and advantages of the device will be readily understood from the foregoing without further detailed explanation.

Having thus described the invention, what I claim is:

1. A marble making machine comprising a guide including an upper part having a cup adapted to receive a stream of molten glass and also including a bottom spaced from the upper part, a cutter bar mounted in the guide for reciprocating movement and having a plurality of cups formed therein and including front and rear cups and a center cup adapted to successively register with the first-named cup, cutters on the upper edges of the second-named cups, and discharge funnels in the bottom of the guide adapted to receive the material from said second-named cups.

2. A marble making machine comprising a guide including an upper part having a cup adapted to receive a stream of molten glass and also including a bottom spaced from the upper part, a cutter bar mounted in the guide for reciprocating movement and having a plurality of cups formed therein and including front and rear cups and a center cup adapted to successively register with the first-named cup, cutters on the upper edges of the second-named cups, and a pair of funnels in the bottom of the guide, one of said funnels being adapted for registry with the front and center cups during progressive forward movement of the cutter bar to successively receive material from the front and center cups, and the other of said funnels being adapted for registry with the center and rear cups during progressive rearward movement of the cutter bar to successively receive material from the center and rear cups.

ORIS G. HANLON.
